(57) **CLAIM**

The ornamental design for a downspout hinged diffuser, as shown and described.

DESCRIPTION

FIG. 1 is a perspective view.

FIG. 2 is a side view of the downspout hinged diffuser in an upright position;

FIG. 3 is a side view of the downspout hinged diffuser in a down and functional position; the sides are mirror images of each other;

FIG. 4 is a top view looking down and into the downspout hinged diffuser;

FIG. 5 is a front view;

FIG. 6 is a rear view; and,

FIG. 7 is a bottom view.

The broken line showing is included for the purpose of illustrating portions of the article and environment and forms no part of the claimed design.
